(No Model.)

J. SANDERS.

EMBROIDERY FRAME.

No. 372,707.

Patented Nov. 8, 1887.

ATTEST,
John H. Redstone
L. E. Redstone.

INVENTOR,
John Sanders.

UNITED STATES PATENT OFFICE.

JOHN SANDERS, OF SAN FRANCISCO, CALIFORNIA.

EMBROIDERY-FRAME.

SPECIFICATION forming part of Letters Patent No. 372,707, dated November 3, 1887.

Application filed January 22, 1887. Serial No. 225,092. (No model.)

To all whom it may concern:

Be it known that I, JOHN SANDERS, a citizen of the United States, residing in the city and county of San Francisco and State of California, have invented a new and useful Embroidery-Frame, of which the following is a specification.

My invention relates to improvements in embroidery-frames, which will be readily understood by reference to the accompanying drawings and the letters referring thereto.

Figure 1 is a perspective view of the frame without the canvas; Fig. 2, a perspective view of the same with a canvas attached and partly rolled, with a sprig of embroidery commenced; and Fig. 3, a front elevation showing a broken part of the lever-standard.

A and B represent the side rails of the embroidery-frame; C and D, the rolls; E and F, the attaching tape or list; G, the embroidery-canvas; H and I, the supporting-arms or standards; J and K, the adjusting-slots for the embroidery-frame; L and M, the set-screws for attaching the embroidery-frame in the supporting-arms; N and O, the pivot-standards; P and Q, the concentrical guide-slots; R, the set-screw for holding the supporting-arms; S, the bed-bar; T, the table front; U, the clamp for clamping to the table; V, the set-screw for setting the clamp U fast to the table; W and X, the ratchet-wheels; Y and Z, the catch-pawls. a and b represent the pivot of the supporting-arms.

The object of my invention is to secure a neat and completely adjustable embroidery-frame, that may be easily adjusted to suit the size of the operator or the height of the table. The following is the construction of the same: I generally form the side rails, A and B, supporting-arms H and I, and bed-bar S of wood, although other material commonly employed in the construction of that class of articles may be used for the same. I form the pivot-standards N and O with concentric guide-slots P and Q, the clamp U and all of the set-screws and bolts and the ratchet-wheel W and X and

pawls Y and Z of such metal as is usually employed in that class of manufacture.

The following is the operation of the same: I generally attach the frame to the front or at either side or end of the table in the position shown in Figs. 1 and 2. If in this position it be too high for the person who is to use it, I turn the supporting-arms H and I down upon the pivots a and b and set the screw R fast in the concentric slots P and Q, thus securing the advantage of the leverage from the pivots a and b to the concentric slots P and Q. I then adjust the canvas as required, by turning the side rails, A and B, upon the set-screws L and M to the required angle. It will be seen that the pivoted frame may be taken out of the slots J and K, when required, by loosening the set-screws L and M, and passed out at the opening d. (Shown in Fig. 3.) It is then freed from the stand, and may be carried in the hand like any simple frame.

Having thus described my invention, what I claim, and desire to secure by Letters Patent, is—

1. In embroidery-frames, the pivoted frame composed of the side rails, A and B, and rolls C and D, having the attaching strips E and F, the ratchet-wheels W and X, and pawls Y and Z, in combination with the bed-plate S, the side rails, H and I, having the slots J and K, the pivot a and b, the set-screws L, M, and R, and the pivot-standards N and O, with guide-slots P and Q, for the purpose of allowing the adjustment described.

2. The slotted supporting-arms H and I, in combination with the pivot-standards N and O and bed-bar S, the pivots a and b, the slots P and Q, and set screws R, for the purpose of securing the required adjustment of the embroidery-frame and maintaining a firm support of the same, constructed and operated substantially as and for the purposes set forth.

JOHN SANDERS.
